UNITED STATES PATENT OFFICE.

DAVID E. Dangler AND HENRY RUPPEL, OF CLEVELAND, OHIO.

VALVE MECHANISM FOR VAPOR-STOVE BURNERS.

SPECIFICATION forming part of Letters Patent No. 376,518, dated January 17, 1883.

Application filed July 2, 1887. Serial No. 243,298. (No model.)

To all whom it may concern:

Be it known that we, DAVID E. Dangler and HENRY RUPPEL, of Cleveland, in the county of Cuyahoga and State of Ohio, have 5 invented a certain new and Improved Valve Mechanism for Vapor-Stove Burners; and we do hereby declare that the following is a full, clear, and complete description thereof.

The nature of our invention relates to the 10 means employed for operating the needle-valve in connection with the vapor generator and burner, as hereinafter set forth and described.

To enable those skilled in this art to understand said invention, reference will be had to 15 the following specification and to the annexed drawings.

Like letters of reference refer to like parts in the several views.

Figure 1, Plate 1, is a front elevation showing the improvement in connection with a vapor generator and burner and parts thereof in section. Fig. 2, Plate 2, is a side elevation. Fig. 3, Plate 1, is a detached detail in perspective.

25 The oil-induction pipe A is connected with a reservoir in the usual way, and its upper end is in open attachment with the vapor generator or retort B, which forms an annular tube around the chamber of the vapor-burner C, of 30 which C' is the semi-spherical wall and C" the burner-cap. The vapor from the generator passes through the pipe D, Fig. 1, into the chamber of the needle-valve casing E, and from the needle-valve opening a it passes through 35 the pipe F to the burner G. This burner consists of an undulating or curved tapering cap with perforations, mounted upon a flat base fastened to the pipe F. The pipe D is attached to the generator B by a screw-connection to 40 the tubular boss H. More than one of such connections may be made with the generator for conveying vapor to the several burners. The pipe I has also a threaded attachment at J with the generator, by which means the vapor is transmitted through the pipe I to the 45 needle-valve chamber in the casing K from the generator B.

Connected to the casing K is a cup, L, for the reception of oil to produce the primal 50 flame in the initial vaporizing of oil in retort or generator B.

Projecting from the casing E is a bracket, M, Fig. 1, on the return or arm c of which is movably fitted the sleeve d of the adjustable bracket N in a line parallel with the needle 55 valve and stem. From the upper part of this bracket extends a bearing, O, Figs. 1 and 2, at right angles, or nearly so, with the line of the needle-valve, the stem P of which is seen in Fig. 1. The cam-rod Q is journaled and 50 supported in this sleeve O, and the cam R is fastened to the end of the said cam-rod.

The needle-valve stem P is attached to a cam-yoke, S, Fig. 3. This yoke is rectangular in form, with a corresponding central space, 65 S', in line with the needle-valve stem. In this space S' is arranged the cam or eccentric R to operate the yoke S by means of the rod Q, so as to cause a reciprocating movement to the yoke and valve stem in opening and closing 70 the needle-valve in the casing E, of which a, Fig. 1, is the valve-opening. When the cam R is turned to the position e, as indicated in Fig. 1 by dotted lines, the valve at a is then closed, cutting off the vapor from the burner. 75 On turning the cam to the position f the yoke is moved back thereby a distance indicated at g. The change of positions or movements of the cam and yoke are indicated by dotted lines e f g, Fig. 1. The valve being thus opened 80 admits of the passage of vapor from the generator or retort B to the burner G, as before stated.

From the rear angle-arm of the yoke S projects a stud, T, which slides in the slot U in 85 the end of the adjustable bracket N, Figs. 1 and 2. This stud and slot act as a guide and support for the yoke, and also determine the travel of the needle-valve in closing it, according to the position of the bracket on the arm 90 c, as the stud T, when moved in contact with the closed end of the slot U, as seen in Fig. 1, arrests the forward movement of the needle-valve. This forward movement or stroke of the needle-valve may be more or less, according 95 to the position of the bracket N upon the arm c. The moving of the bracket N upon the arm c in direction of the arrow causes the eccentric or cam to move the yoke with the needle-valve connection, correspondingly as 100 the sweep of the cam less than a full stroke is arrested at the desired point of closing the

valve by the stud T being brought in contact with the closed end of the slot U, which prevents the needle-valve from being forced or unduly pressed into the valve-opening a. This 5 arresting of the valve from being unduly forced into the valve seat or opening causes the valve and seat to endure much longer without leakage than when used in the ordinary way. In case the needle valve and seat become so worn 10 as to leak, it may be remedied by moving in direction of the arrow the bracket N on the arm c sufficiently to cause the cam R to press the valve more tightly on its seat. The open end of the slot U admits of the needle-valve 15 being drawn back from its seat the full stroke of the cam.

On first adjustment of the needle-valve mechanism described, the full eccentric stroke of the cam R is restricted by means of the stud 20 T being brought in contact with the closed end of the slot U, as before stated, by which means the valve-opening is relieved from undue pressure of the needle-valve.

In case of leakage by use, the full stroke of 25 the cam not being sufficient to arrest the leak on closing the valve, then the bracket N may be moved on the arm c in direction of the arrow, thereby exerting more force by the cam without its full stroke to close the valve more 30 effectively.

The arm c not only admits of the bracket N moving longitudinally thereon, but it also permits an axial and lateral or vibratory movement for adjusting the cam and yoke in position 35 with relation to the bracket and rod Q, as shown in Figs. 2, 3, in which it will be seen that the cam is movably arranged in space S', between the bracket N and yoke. The bracket is retained in its adjusted position by means of 40 the set-screw V, which passes through the sleeve d and fastens upon the arm c.

In the preceding description the needle-valve mechanism has referred more particularly to a horizontal needle-valve. The improvements are, however, applicable to a 45 needle-valve in an angular or perpendicular position. In Fig. 1 both the perpendicular

and horizontal positions of the valve mechanism are represented and arranged substantially in the same way, the difference being in position only; and Fig. 2 is a different view of essentially the same construction and adjustment of the needle-valve devices and attachments as that shown perpendicularly in Fig. 1.

To avoid prolixity the specification more particularly refers to the improvements applied to the horizontal valve.

What we claim as our invention, and desire to secure by Letters Patent, is—

1. In a vapor-burner, the adjustable bracket 60 N, movably connected in relation to the arm c, and having a slot, U, closed at one end, a yoke, S, with a stud engaging said slot, a cam arranged in connection with said yoke in central line, or nearly so, with the needle- 65 valve, and a cam-rod having its support in the bracket for operating said cam for the movement of the needle-valve, substantially as described, and for the purpose set forth.

2. The combination, with a vapor-burner, 70 of a cam, R, movably arranged in connection with the yoke S, for operating the needle-valve by means of a rod having its bearing in a bracket on one side of said cam, and a slot at one end for the reception of a stud projecting 75 from the yoke and of an arm, c, for carrying said bracket and to admit of its longitudinal and axial movement thereon, substantially as and for the purpose specified.

3. The combination, with the bracket N, having an axial and longitudinal movement upon the arm c and attached thereto in a line parallel with the needle-valve, of a cam arranged within the yoke, connected with the stem of the needle-valve and operating conjointly in 85 connection with a vapor-burner, substantially as and for the purpose set forth.

In testimony whereof we affix our signatures in presence of two witnesses.

DAVID E. DANGER.
HENRY RUPPEL.
